The ornamental design for a mirror bracket, as shown and described.

DESCRIPTION

FIGS. 1–7 illustrate a first embodiment of our novel design suitable for use on the left or driver's side of a motor vehicle.

FIG. 1 is an oblique view of a mirror bracket showing our new design;

FIG. 2 is a frontal view of the mirror bracket shown in FIG. 1;

FIG. 3 is a side view of the mirror bracket shown in FIG. 2; FIG. 4 is an opposite side view of the mirror bracket shown in FIG. 2;

FIG. 5 is a rear view of the mirror bracket shown in FIG. 2; FIG. 6 is a top view of the mirror bracket shown in FIG. 2; and,

FIG. 7 is a bottom view of the mirror bracket shown in FIG. 2.

Our novel design also includes a second embodiment suitable for use on the right or passenger side of a motor vehicle which is mirror symmetrical to FIGS. 1–7 and therefore not separately illustrated.
